UNITED STATES PATENT OFFICE.

SAMUEL STOWELL, OF VANCOUVER, BRITISH COLUMBIA, CANADA.

PAPER-HOLDING DEVICE.

Application filed January 24, 1927. Serial No. 163,239.

My invention relates to improvements in paper holding devices which are particularly adapted for use with printing presses of the Gordon or similar type. The objects of the invention are to provide means for holding each sheet of paper in firm contact with the platen when the printing to be done thereon is of such width as to prevent the paper being satisfactorily held by the grippers of the machine. Frequently the type or plate used is of a width approximately equal to the width of the paper, though spaces frequently occur between some of the lines, or within the width of the sheet where no printing is to be done, in which spaces a grip could be applied, it is therefore the object of this invention to grip the paper at one or more of these spaces.

The invention consists essential of one or more fingers carried directly or indirectly by the grippers, which are brought into contact with the paper by the movement of the grippers, which fingers are adapted to be resiliently pressed into firm engagement as the bed approaches the platen, as will be more fully described in the following specification, in which:—

Fig. 1 is a general view of the invention as applied to a Gordon press.

Fig. 2 is a rear elevational view of a gripping finger.

Fig. 3 is a sectional view.

Fig. 4 is a view showing the invention adapted to be applied from the upper end of the paper to be printed.

In the drawings like characters of reference indicate corresponding parts in each figure.

The numeral 1 indicates generally a Gordon press of which 2 is the bed upon which the type is to be mounted and 3 is the platen which is fitted in the usual manner with a pair of laterally adjustable grippers 4.

The numeral 5 indicates generally a gripping finger which is preferably formed of a strip of light sheet metal pierced adjacent one end in the form of an H to define a pair of oppositely directed tongues 6, which are outwardly bent at right angles to the thickness 50 of the metal in the grippers as at 7 when they are again bent parallel to the finger as at 8 so as to provide a resilient engagement with the

gripper so that the finger may be easily moved along the gripper to any desired position.

On the rear face of the gripping finger 5 is 55 a pad 9 of rubber, cork or other suitable material which is adapted to be engaged by the bed 2 of the machine as it swings into contact with the platen. When it is desired to use one or more gripping fingers projecting 60 lengthwise of the paper to be printed, I provide a connecting bar 10 rectangular in cross section, which is adapted to be detachably secured to the grippers 4 by any suitable means as at 11, and upon this bar one or more 65 gripping fingers 5 are mounted and are moved into such a position as to engage the paper sheet in places where no printing is to be done.

Having thus described the several parts of 70 my invention I will now briefly explain its use.

When it is desired to provide for gripping a sheet of paper which is to be printed with type reaching closely to its marginal edges, 75 the grippers 4 are moved outwardly in opposite directions beyond the width of the paper, gripping fingers 5 of any suitable length are placed thereon and are moved into such a position as to avoid the type and to bear 80 upon the margin edges of the paper as the bed 2 and its type is moved into contact with the paper sheet upon the platen. Should it be desired to grip the paper from its end, the connecting bar 10 is applied to the grippers 85 and gripping fingers fitted thereon, which are adjusted as to position as previously described. As the type upon the bed is brought into contact with the paper sheet, portions of the type frame or bed are brought 90 into contact with the pad 9 thus imposing a resilient pressure therethrough onto the paper to hold it immovable during the printing, and preventing the production of slurs or other defects which render the work unacceptable to the purchaser. 95

It will be obvious that the gripping fingers 5 may be of any length or provided with any other suitable method of attachment to the grippers, and also that a flat steel spring may 100 be used thereon in place of the resilient pad 9 shown.

What I claim as my invention is:

The combination with a printing press hav-

ing a type supporting bed and a paper sheet carrying platen adapted to approach and re-cede from each other, and a pair of grippers adapted for movement to and from the platen, 5 of a finger comprising a strip of sheet material having a pair of opposed tongues adapted to embrace one of the grippers and a re-

silient non-metallic pad upon the finger which is adapted to be engaged by the bed or its type for exerting pressure therethrough to the 10 paper sheet.

Dated at Vancouver, B. C., this 15th day of January, 1927.

SAMUEL STOWELL.
